UNITED STATES PATENT OFFICE.

WILLIAM P. HOPKINS, OF LAWRENCE, MASSACHUSETTS, ASSIGNOR TO GORDON MCKAY, OF NEWPORT, RHODE ISLAND, AND JAMES W. BROOKS, OF CAMBRIDGE, MASSACHUSETTS, TRUSTEES.

NAILING-MACHINE.

SPECIFICATION forming part of Letters Patent No. 289,103, dated November 27, 1883.

Application filed October 12, 1883. (No model.)

To all whom it may concern:

Be it known that I, WILLIAM P. HOPKINS, of Lawrence, county of Essex, State of Massachusetts, have invented an Improvement in 5 Nailing-Machines, of which the following description, in connection with the accompanying drawings, is a specification, like letters on the drawings representing like parts.

This invention in nailing-machines has for 10 its object to prevent the sticking or lodging of nails in the roadway; and it consists in the combination, with a roadway, of one or more strikers, to strike those nails which are too far above the top of the roadway, or which get 15 lodged upon or above the roadway, or become stuck among the other nails, and do not drop and hang into the roadway.

This invention is an improvement on that 20 class of nailing-machines having a chute or chutes, such as represented in United States Letters Patent No. 265,227, dated September 26, 1882, to which reference may be had.

Figure 1, in side elevation, represents an ordinary roadway or chute of a nailing-machine 25 with my improvements added; Fig. 2, a top view thereof; Fig. 3, a vertical longitudinal central section; and Fig. 4, a cross-section of the roadway or chute on the dotted line $x-x$, Fig. 1.

30 The chute or roadway m may be considered to be the same as the chute designated by the same letter in the patent referred to, and the shaft a may be driven from a shaft such as shown in the said patent, and marked C, 35 it having a gear to drive an intermediate gear in engagement with the gear b . Shaft a has its bearings in suitable standards, $c c$, herein shown as erected from the roadway or chute. The shaft a has upon it two shouldered cams, 40 $d d'$, herein shown as double-shouldered, (see Fig. 1,) which are rotated in the direction of the arrows thereon, and which act against pins $e f$ of strikers $e' f'$, made as pointed and beveled bars, placed upon or above the roadway m , so as to slide horizontally just above 45 the top of the roadway, and also act as partial covers for the roadway, the said strikers having, respectively, a connected spring, $g g'$,

attached to a suitable post, h or h' , or to the head of the nailing-machine, or to a suitable 50 fixed part of the said machine, the said springs acting normally to keep the pins $e f$ against the cams $d d'$. The under sides of the strikers are located sufficiently far above the top of the roadway to permit the passage of 55 the heads of the nails to be driven between the said strikers and the roadway, as represented, by the heads of those nails which have passed under the upper ends of the strikers. If any of the nails fail to drop down 60 between the side bars or rails of the roadway, as represented by nail 2 in Fig. 3, or if a nail becomes lodged across the roadway, as shown by nail 3 in Fig. 2, it will be struck by the front ends of the strikers as they are 65 thrown toward the upper end of the roadway by the cams $d d'$, thus striking the said nail a blow and causing it to fly off the roadway. If lodged, as the nail 3, or if held up, as nail 2, 70 it and the nails behind it will be moved or thrown backward toward the receiving end of the roadway, and before the nail next comes against the striker it will have had a chance to fall properly into the roadway, for the striker, as the pins $e f$ pass the corners 75 of the cams, will be actuated by the springs g or g' , connected with them, at a speed faster than the nail can descend in the roadway by gravity, and hence, the path of the nail on the roadway being unobstructed for a short 80 distance, the nail will be free to respond to gravity and fall farther into the space between the sides of the roadway, where the under side of its head will be supported by the top of the roadway, when the nail will be free to pass 85 under the striker, which will reciprocate over its head.

My improvements may be added to any well-known nailing-machine in which it is possible to feed headed nails down a roadway, to 90 be taken therefrom singly by a separator and delivered to a driver, said machine being provided with suitable gearing to rotate the shaft a .

I claim—

1. The roadway combined with a recipro-

cating striker, to strike against and move upward toward the receiving end of the roadway such headed nails as are not properly lodged in the said roadway, substantially as described.

5. 2. The roadway and the rotating shaft provided with cams, combined with the striker, located just above the roadway and moved by the said cams to strike imperfectly-lodged nails, substantially as described.

In testimony whereof I have signed my name to this specification in the presence of two subscribing witnesses.

WILLIAM P. HOPKINS.
